UNITED STATES PATENT OFFICE.

ALEXANDER T. BROWN, OF SYRACUSE, NEW YORK.

TYPE-WRITING MACHINE.

No. 852,374.

Specification of Letters Patent.

Patented April 30, 1907.

Original application filed June 4, 1904, Serial No. 211,128. Divided and this application filed October 21, 1904. Serial No. 229,486.

To all whom it may concern:

Be it known that I, ALEXANDER T. BROWN, a citizen of the United States, and a resident of Syracuse, in the county of Onondaga and State of New York, have invented certain new and useful Improvements in Type-Writing Machines, of which the following is a specification.

My invention relates to typewriting machines and more especially to the type and key actions of such machines.

My invention consists in certain features of construction and combinations and arrangements of parts, all as will be hereinafter more fully described and particularly pointed out in the claims.

This application is a division of my application Serial No. 211,128, filed June 4th, 1904.

20 My invention is illustrated in the accompanying drawings in which,

Figure 1 is a front to rear vertical section of a typewriting machine; Fig. 2 is a top plan view of a link used in my construction; Fig. 3 is a perspective view of the type bar operating link; and Fig. 4 is a plan view, partly in section, of the key action.

30 The main frame of the typewriter illustrated in the accompanying drawings comprises a base portion having side plates 1 connected together by a combined back plate and shelf 1', to which they are detachably secured, as by screws. Posts 2 rising from said side plates support a top plate 3 on which is mounted a carriage which supports the platen 4.

40 The keyboard mechanism is mounted in a secondary frame which is detachably mounted in the main frame of the machine. Said detachable secondary frame comprises a series of plates 5 which are strung on rods 6 and spaced apart on said rods by washers or sleeves 7. Each of the rods 6 is threaded near one or both of its ends and nuts 8 on said threaded ends hold the plates 5 and washers 7 in position, the whole thus constituting a rigid framework. This framework is mounted in the main frame by means of the reduced ends of the rods 6, which are inserted in suitable openings in the side plates 1 of the main frame, as shown in Fig. 4. Furcated key levers 9 are mounted on sleeves 10 which are strung on rods 11 extending through the series of plates 5. These key levers are ar-

ranged in straight rows from front to back of the machine, and a plate 5 extends between each contiguous pair of rows of key levers. These key levers 9 are formed of sheet metal bent into a U-shaped form at 12, thus forming furcated levers, the front ends of which are comparatively close together and embrace bars 13 into which project the stems 14 of the keys 15. At their rear ends the furcated levers 9 are spread farther apart so that when a key is depressed the front end of its lever 9 may descend between the arms of the furcated key lever next in front of it. The stems 14 are guided in openings in frame plates 16 beneath which washers 17 of felt or other sound deadening material are secured to the rods 13. Each of the levers 9 is rigidly secured to a sleeve 10 which is loosely mounted on a rod 11 and each of these sleeves has fixed thereto a lever arm 18 to the upper end of which is pivoted a parallel moving link 19 which transmits the motion of the key to the type bar. The keyboard system so far described is substantially identical with that shown and described in my prior application, Serial No. 127,536, filed October 16, 1902, typewriting machines.

50 A series of secondary levers 20 are pivoted at 21 on a bar 22 which extends transversely of the machine. Two or more of the plates 5 are extended toward the back of the machine 85 and support the bar 22 which is secured thereto by screws 23, as shown. The levers 20 are connected to the lever arms 18 by the links 19, each of which is pivoted at its front end to one of the lever arms 18 and at its rear end to one of the levers 20. The levers 9 are so arranged as to place the keys 15 in straight rows from front to back of the machine; but the lever arms 18 are mounted on the sleeves 10 at different positions longitudinally of said sleeves, as shown in Fig. 4, so that one of said arms stands substantially directly in front of each of the levers 20. As shown in the present case, the arm 18 nearest the back of the machine is mounted on its sleeve 10 near the right-hand end of said sleeve, the arm 18 nearest the front of the machine is near the left-hand end of its sleeve 10, and the other arms occupying intermediate positions, as shown. I prefer to make the arms 18 and 20 of the same length and to so design the parts that these two arms are parallel. This being the case, each of the links 19 has a

parallel motion, that is to say, when a key is depressed every point of the link 19 connected thereto moves parallel to every other point. Each of the levers 20 extends downward from its pivot, beneath which it is formed with a hook 24 to which is connected one end of a spring 25, the other end of which is connected to one of a series of hooks 26 formed by bending back the teeth of a comb plate 27, which is secured to the plates 5 and extends across the keyboard mechanism. The springs 25 hold the keys in their normal positions. Each of the levers 20 has an arm 28 extending toward the back of the machine and lying beneath a universal bar 29 which has rigidly secured to its ends arms 30 which are pivoted at 31 to the side plates 1 of the main frame. The construction is such that when any key 15 is depressed, its furcated lever 9 and lever 20 arm 19 are rocked, thus rocking the corresponding lever arm 20 and raising the universal bar 29 by the lever arm 28. The universal bar may be connected with the escapement mechanism and other devices in any suitable manner.

The type bars 33 are mounted upon a rod 34 by a ball bearing connection. The rod 34 is bent into the segment of a circle and has grooves or ball races cut in its surface. The 30 type bar, at the point where it surrounds the rod, is made of two pieces, a semi-circular strap 35 being secured to the bar by screws 36, thus forming a circular opening or eye which is grooved internally to form a ball 35 race co-operating with that formed in the rod 34. Two types 37 and 38 are mounted on each type bar, and the segment 34 is shiftable up and down to bring one or another of said types to the printing point. The precise construction of type bar segments and ball bearing here shown are immaterial to the present invention, but are described and claimed in other applications of mine copending herewith. Each of the parallel moving links 19 40 has an upwardly extending arm 39 which is pivoted at 40 to a link 41 which is pivoted at 42 to a type bar 33. The link 41 consists of a strip of resilient sheet metal which is bent in the manner shown in Fig. 3 and has ears 43 45 bent back from its edges and embracing a portion of the type bar 33 to which said ears are pivoted at 42. At its forward end the link 41 is formed with a pair of ears 44 which are bent back as shown and pivoted to the arm 50 49 at 40. The form of the link 41 is such that said link constitutes in effect a spring connection between the arms 39 and the type bar. I have found that this form of connection greatly improves the touch on the key. 55 For example, when the type strikes the platen, the key is not violently or suddenly arrested but is arrested only through this resilient link which lessens the shock on the finger of the operator.

60 The type bars 33 are arranged segmentally,

those type bars which are near the end of the segment lying at a greater distance above the links 19 than those near the center of the segment and also lying in different planes at different inclinations to the vertical. The 70 arms 39 which are connected to those type bars near the ends of the segment are accordingly made longer and at their upper ends are bent into the planes of their respective type bars. By an inspection of Fig. 1 it will be 75 seen that the forwardly extending portion of the links 19 are all alike except as to length. In practice, therefore, when these links are made, they are all blanked out alike, each one having its arm 39 of sufficient length to 80 reach the highest type bar of the segment and each having its forwardly extending arm of sufficient length to reach the key lever of the front row. Each of these blanks then has its forwardly extending arm cut off to the 85 proper length and bent back upon itself as shown at 45 (Fig. 2) so that the lever arm 18 is pivoted between the forwardly extending arm of the link 19 and the backwardly bent end of that arm. At its rear end each of the 90 levers 19 is bent back upon itself as shown at 46 and the lever arm 20 is pivoted between the link and the bent back portion thereof. Each of the arms 39 is cut off, if necessary, to a length appropriate to the 95 height of the particular type bar to which it is to be connected. The construction of the keyboard mechanism is such that the levers 9 and 18, the bell crank levers 20, 28, the links 19 and springs 25 are all assembled 100 outside of the machine in the detachable frame which has been described, and this part of the mechanism is inserted in the machine as an entirety.

In assembling the machine, the key-action 105 frame comprising the plates 5 and rods 6 and the entire key action, including the levers 20 and links 19, may be assembled before they are put into the machine. The main frame of the machine may then be assembled 110 except for one of the side plates 1. The key action frame may then be placed in position, one of the reduced ends of each of the rods 6 being inserted in the openings in that side plate 1 which is already in position. The 115 remaining side plate may then be placed in position, the other ends of the rods 6 inserted in their openings, and said side plate may then be secured to the back plate 1' and the posts 2 to the top plate 3. The plates 16 120 may then be secured in position, and the links 41 may be connected to the arms 39 by springing the ears 44 over the pins 40. The key-action frame and key action may be detached as an entirety by reversing this operation.

Various changes in the details of construction and arrangement may be made without departing from the gist of my several improvements.

The ball bearing for the type bar shown and briefly described herein, is claimed in my pending application Serial No. 201,260 filed April 2nd, 1904. In my prior application Serial No. 127,536, hereinbefore referred to, there is shown a type action embodying the bell crank key levers, the secondary levers similar to the levers 20, 28 and the parallel moving links 19 with their upstanding arms 39 of different lengths connected with the type bars by links corresponding to the links 41; but in said prior application the secondary levers are mounted on a cross bar which is secured to the main frame of the machine instead of to the detachable auxiliary frame as in the present case. This general style of key and type action is claimed in said prior application, many of the claims of which read on the present construction. In said prior application the detachable frame having the key levers mounted therein is also claimed more broadly than in the present case and various details of the key and type action shown in this case are claimed in said prior application. The claims in the present case are limited to a construction in which the secondary levers are carried by the detachable frame and also to the particular construction of the link 41 which is specifically different from that shown in said prior application. As shown in the present case, the top plate extends out in front of the front face of the platen and serves as a dust guard to protect the type bar bearings from falling dust. This feature is claimed in my prior application, Serial No. 201,260, above referred to.

What I claim as new and desire to secure by Letters Patent, is:—

40. 1. In a typewriting machine, the combination with the main frame; of a frame detachably fixed in said main frame; a series of key levers mounted in said detachable frame; a series of secondary levers mounted in said detachable frame and operatively connected with said key levers; and a universal bar operated by said secondary levers.
45. 2. In a typewriting machine, the combination of a link consisting of a curved strip of resilient sheet metal having one or more ears struck up therefrom at each end; a type bar pivotally connected to the ear or ears at one end of said link; and a key actuated member pivotally connected to the ear or ears at the other end of said link.
50. 3. A type bar operating link consisting of a curved strip of resilient sheet metal having at its end a pair of ears bent back from its edges.
55. 4. In a typewriting machine, the combination with the main frame, of a frame detachably fixed in said main frame and comprising parallel plates extending from front to back of the machine, parallel transverse rods supported by said plates, and a transverse bar

rigidly supported by said plates; key levers mounted on said parallel rods; secondary levers mounted on said transverse bar; and links connecting said key levers and said secondary levers.

5. In a typewriting machine, the combination of a main frame; a series of front-strike upwardly and rearwardly striking type bars mounted in said main frame; a secondary frame comprising cross-rods supported by plates extending fore and aft of the machine and supported by said cross rods, and a cross bar supported by said plates; key levers supported by said plates; secondary levers supported by said cross-bar; parallel moving links connecting said key levers and secondary levers; and means separate from said secondary levers connecting said parallel moving links with said type bars.

6. In a typewriting machine, the combination of a main frame; a series of front-strike type bars mounted in said main frame; a secondary frame detachably fixed in said main frame; key levers and secondary levers mounted in said detachable frame; parallel moving links connecting said key levers with said secondary levers; and links directly connecting said parallel moving links with said type bars.

7. In a typewriting machine, the combination of a main frame; front-strike type bars mounted in said main frame; a secondary frame detachably fixed in said main frame and comprising transverse rods supported by said main frame, and a series of plates mounted on said rods; key levers and secondary levers supported by said plates; parallel moving links connecting said key levers and secondary levers; links directly connecting said parallel moving links with said type bars; and a universal bar operated by said secondary levers.

8. In a front-strike typewriting machine, the combination of a main frame, a platen mounted to travel on said main frame, upwardly and rearwardly striking type bars that impact against the front face of the platen, an auxiliary frame detachably fixed in the main frame so that the auxiliary frame and the parts carried thereby may be inserted in and removed as a whole from the main frame, key levers and secondary levers carried by said auxiliary frame, and intermediate links between said key levers and secondary levers, the connections between said key levers and type bars being effected through said intermediate links.

9. In a front-strike typewriting machine, the combination of a main frame, a platen mounted to travel on said main frame, upwardly and rearwardly striking segmentally arranged type bars that impact against the front face of the platen, an auxiliary frame detachably fixed in the main frame so that

the secondary frame and the parts carried thereby may be inserted in and removed as a whole from the main frame, key levers, and secondary levers carried by said auxiliary frame, said levers having upright substantially parallel members, intermediate links between the upright members of said key levers and secondary levers, type bar actuating links between the type bars and said in-

termediate links, and a universal bar actuated by said secondary levers.

Signed at Syracuse, in the county of Onondaga and State of New York, this 17th day of October, A. D. 1904.

ALEXANDER T. BROWN.
